UNITED STATES PATENT OFFICE

CHARLES P. SHINN, OF NEW YORK, N. Y.

DESIGN FOR A SANDWICH BOARD

Application filed May 13, 1930. Serial No. 35,626. Term of patent 7 years.

To all whom it may concern:

Be it known that I, CHARLES P. SHINN, a citizen of the United States, residing at New York, county of New York, State of New York, have invented a new, original, and ornamental Design for a Sandwich Board, of which the following is a specification, reference being had to the accompanying drawing, forming a part thereof.

The figure is a perspective view of a sandwich board showing my new design.

I claim:

The ornamental design for a sandwich board, as shown.

CHARLES P. SHINN.
